UNITED STATES PATENT OFFICE.

OVE H. ARNESEN, OF ST. PAUL, MINNESOTA.

CLAMP.

1,137,109.

Specification of Letters Patent. Patented Apr. 27, 1915.

Application filed April 11, 1914. Serial No. 831,201.

To all whom it may concern:

Be it known that I, OVE H. ARNESEN, subject of the King of Norway, residing at St. Paul, in the county of Ramsey and State 5 of Minnesota, have invented a new and useful Improvement in Clamps, of which the following is a specification.

The object of this invention is to provide a clamp which is adapted for use in making 10 square and miter joints.

The invention has to do more particularly with an ordinary clamp such as is commonly employed by carpenters for drawing two faces together to form a close and even 15 joint, said clamp being provided with movably mounted jaws which are adapted to engage the parts of a miter joint uniformly and evenly together and hold them in that position until permanently fastened. The 20 jaws also are so arranged that they can be moved back out of the way leaving the ordinary jaws of the clamp free for ordinary use.

Further objects of the invention will be 25 apparent from the following description, and particularly pointed out in the claims.

In the accompanying drawing forming part of this specification, Figure 1 is a side elevation of my invention showing the parts 30 of a miter joint secured by the clamp; Fig. 2 is a side elevation of a detail illustrating one end of one of the jaws with its auxiliary jaw in substantially the same position as illustrated in Fig. 1; Fig. 3 is another side 35 elevation of a detail illustrating one end of one of the jaws, part of said jaw being broken away and in section for the purpose of more clearly illustrating the construction of the invention; Fig. 4 is a section of 40 a detail taken on the line X—X of Fig. 1, and Figs 5 and 6 are perspective views of parts of my improvement.

In the drawing, A and B indicate two oppositely disposed jaw members of an ordinary carpenter's clamp which are adapted 45 to be adjusted by means of the screws 2 and 3 in the ordinary manner. This clamp is adapted for use in securing the two members together in parallel position in the usual manner. These main jaw members are not adapted for direct use in securing two faces at an obtuse angle together and for more efficiently accomplishing this result, 50 I provide a pair of similarly constructed auxiliary jaws C and D, each of which is mounted in one of the main jaw members

A and B. Each auxiliary jaw consists of a metal face plate 4 having a supporting rib 5 centrally and longitudinally disposed on one side, said rib being adapted to be seated in a slot 6 in the main jaw. The lateral face of the plate 4 opposite the side from which the rib projects is provided with inwardly facing teeth 7 trending inwardly and downwardly when the plates engage 60 two members of a miter joint such as G and H illustrated in Fig. 1. The rib on the auxiliary jaw member is formed with a longitudinal slot 8. The main jaw members are provided with pintle members E and F 65 which are similar, one pintle being seated on each main jaw. Each pintle is formed with a yoke 9 integral with two face plates 10—10, said yoke passing through said longitudinal slot 8 in the rib of an auxiliary 70 jaw and across the slot 6 in a main jaw and acting as a pivot on which the auxiliary jaw is free to slide and hinge. The face plates 10—10 are secured across the inner face of the upper end of the main jaw as illustrated 75 such as by screws 11. These face plates 10—10 serve to reinforce and protect the upper ends of the main jaws from wear when the jaws are in ordinary use. The pintle member permits the auxiliary jaw, to turn 80 freely either into position for use in securing the members of a miter joint together, or to swing back out of the way and against the slanting outer faces 12 on the upper ends of the main jaws as illustrated in Fig. 3. 85 The upper end of the slot 8 in each rib 5 is offset to form a pocket 13 which is adapted to receive the yoke 9 and its shoulders to prevent the auxiliary jaw sliding when in extended position. When in extended position 90 the auxiliary jaw is free to swing on its pintle which rests in said pocket whereby both auxiliary jaws are adapted to adjust 95 themselves so that their inwardly and downwardly slanting teeth will bite into the material of the members G and H and hold said members closely joined together. The inner side of the slot 8 toward the face plate 4 is at a slight angle inwardly toward the lower end of the inner wall of said face 100 plate, so that a binding engagement is produced between the inner face of said face plate and the inclined surface 12 of the main jaw when the auxiliary jaw is swung up and slid down upon the face 12. This binding 105 engagement as illustrated in Fig. 3 holds the auxiliary plate with its ribs receded into 110

the main jaw and its face entirely out of the way leaving the main jaw free for ordinary use. When it is desired to use the clamp for securing the members of a miter 5 joint together the auxiliary jaws are moved outwardly and slid inwardly with their pockets 13 holding the pintle yokes 9. The members G and H are then inserted between the face plates of the auxiliary jaws and the 10 screws 2 and 3 tightened, thus causing the teeth 7 to engage the material of the members G and H and clamp said members with their adjacent faces tightly impinged and forming a close joint.

15 In accordance with the patent statutes, I have described the principles of operation of my invention, together with the apparatus which I now consider to represent the best embodiment thereof, but I desire to have 20 it understood that the construction shown is only illustrative, and that the invention can be carried out by other means and applied to uses other than those above set forth within the scope of the following claims.

25 Having described my invention, what I claim as new and desire to protect by Letters Patent is:—

1. A clamp, comprising, in combination, a pair of main jaws having slots in substantial alinement across their outer ends, means 30 for adjusting said jaws apart, an auxiliary jaw carried by each of said main jaws, consisting of a plate, having a series of inwardly and downwardly trending teeth carried by its face and a rib on the back of said plate, said rib being formed with a slot trending at an angle to the adjacent face of said plate and terminating at one end in an offset pocket, said rib being movably seated 35 in the slot in one of said main jaws and a pintle passing across the space between the sides of the slot in each main jaw and through the slot in the rib of an auxiliary jaw and adapted to form a pivot for the 40 auxiliary jaw, said pintle member being adapted to permit said auxiliary jaw swinging 45 back over the upper end of the main jaw and the trending of said slot causing said plate to bind with one of its faces binding 50 against the back of the main jaw.

Copies of this patent may be obtained for five cents each, by addressing the "Commissioner of Patents, Washington, D. C."

2. A clamp, comprising, in combination, a pair of main clamping jaws, means for adjusting said jaws apart and an auxiliary jaw pivoted upon each of said main jaws having a toothed work engaging surface 55 adapted to lie at an obtuse angle to the working surface of the opposite main jaw and a slotted member co-acting with said pivot connection, permitting said auxiliary jaw swinging and sliding back free of the 60 working surface of the main jaw on which it is mounted.

3. A clamp, comprising, in combination, a pair of main clamping jaws having bifurcated upper ends, means for adjusting 65 said jaws apart and an auxiliary jaw slidably engaged within the bifurcated end of each of said main jaws having a work engaging surface adapted to lie at an obtuse angle to the working surface of the opposite 70 main jaw or to slide back free of the working surface of the main jaw on which it is mounted.

4. A clamp comprising a pair of main clamping jaws having slots therethrough, 75 means for adjusting said jaws apart, and an auxiliary jaw slidably engaged within the slots of each of said main jaws adapted to adjust itself to and bear against the adjacent face of a miter joint and to be slid 80 back free of the working surfaces of said main jaws.

5. A clamp comprising a pair of main clamping jaws having bifurcated upper ends, a pivot pin extending through each 85 of said bifurcated ends, means for adjusting said jaws apart, and an auxiliary jaw slidably engaged by said pivot pin within the bifurcated end of each of said main jaws adapted to operatively engage the adjacent 90 face of work lying at an angle to the working faces of said main jaws.

In testimony wheroft, I have signed my name to this specification, in the presence of two subscribing witnesses.

OVE H. ARNESON.
